UNITED STATES PATENT OFFICE.

ALFRED ROSS JARMAN, OF PHILADELPHIA, PENNSYLVANIA, ASSIGNOR OF ONE-HALF
TO R. GORDON GRANVILLE, OF NEW YORK, N. Y.

OSCILLATING VALVE.

1,339,110.

Specification of Letters Patent.

Patented May 4, 1920.

Application filed February 16, 1918, Serial No. 217,543. Renewed March 3, 1920. Serial No. 363,082.

To all whom it may concern:

Be it known that I, ALFRED ROSS JARMAN, a citizen of the United States, residing at Philadelphia, in the county of Philadelphia and State of Pennsylvania, have invented 5 certain new and useful Improvements in Oscillating Valves, of which the following is a specification, reference being had therein to the accompanying drawing.

10 My invention relates to internal combustion engines and especially to a valve structure of the oscillating type.

An object of my invention is to provide 15 a valve structure of the above type which will be capable of high speed in operation with a minimum amount of strain and wear on the working parts.

Another object of my invention is to provide 20 an integral structure in the form of a cylinder head adapted to be used on existing types of internal combustion engines and containing in itself a combustion chamber and valve mechanism therefor.

A further object of my invention is to so 25 combine the shapes, proportions and arrangement of the different elements of the structure as to facilitate rapid charging and thorough scavenging of the combustion chamber.

30 Other objects of my invention will be apparent from a perusal of the following specification and the accompanying drawings.

My invention is illustrated in the accompanying drawings in which—

35 Figure 1 is a top view taken on the line 1—1 of Fig. 2.

Fig. 2 is a longitudinal section taken on the line 2—2 of Fig. 1.

40 Fig. 3 is a longitudinal section taken on the line 3—3 of Fig. 1.

Referring to the drawings in detail, 1 indicates the engine cylinder which may be of any known type fitted with the usual piston 45 2. For the purpose of applying my invention to the usual type of engine, I provide the upper portion of the cylinder with flanges 3 and an inner counter-bore 4 ground in the usual manner for making a tight 50 joint. The valve structure consists generally of the water-jacketed dome or head 5, the telescoping valve sleeves 6 and 7 fitted over the head, and the valve cap 8 fitted over the sleeves and head. The valve head 55 is provided at the bottom with a down-

wardly projecting ledge 9 and outwardly projecting flange 10 fitted to the counterbore 4 and flange 3 respectively, of the engine cylinder, and has a combustion chamber 11 formed therein extending upwardly over the top of the inside of the engine cylinder in the form of a truncated wedge. The outer wall of the head 5 is cylindrical and intake and exhaust ports, 12 and 13 respectively, are provided in opposite sides of the head, 60 which open into the wedge-shaped combustion chamber through the opposite parallel sides 14 and 15, respectively, and near the apex. A threaded bore 16 is provided in the top of the head to receive and hold the usual 70 spark plug near the apex of the wedge-shaped combustion chamber. Between the inner, outer and top walls of the valve head 5 is formed the water jacket space 17 which may be connected to the water circulating 75 system (not shown) in any suitable manner. Annular channels 18 are provided in the outer cylindrical walls of the valve head, two above and one below the ports and are fitted with piston rings 19.

The inner valve sleeve 6 is seated around the cylindrical wall of the head 8 and the outer valve sleeve 7 is seated around the outer surface of the inner valve sleeve, the adjacent surfaces of the valve sleeves and 80 head being suitably ground or otherwise finished to form a close fit. A ring of anti-friction metal 19' is fitted around the bottom of the head between the head flange 10 and the valve sleeves. The inner valve 90 sleeve 6 is provided with an operating arm 20 which extends radially and outwardly from the upper edge of the sleeve and the outer sleeve 7 is also provided with an operating arm 21 which extends outwardly and 95 radially from the edge of the recessed portion 22 in the sleeve 7 through which the arm 20 of the inner sleeve projects. This arrangement permits the sleeves to be oscillated about the axis of the head by means 100 of their respective operating arms which may swing freely one above the other.

The valve cap 8 is arranged to fit down over the head and valve cylinders and is held in place thereon by means of the annular flange 23 which is made to register with the flanges 10 and 3 of the head and engine cylinder, all three flanges being clamped together by means of suitable bolts 105 25. The top of the cap is open and provided 110

with an inwardly extending flange 26 which acts to bridge the space between the wall of the cap and the head and hold the valve sleeves against upward movement. A perforated washer or ring 27 of anti-friction material is fitted between the flange 26 and the upper edges of the valve sleeves to prevent wear thereon. Lubricating oil may be fed between the relatively moving surfaces 5 through a suitable oil supply pipe such as 29 passing through the flange of the cap and the anti-friction ring 27 at a point above the engaging surfaces of the valve sleeves. In order to induce even distribution of oil around the engaging surfaces of the valve sleeves, I provide spiral grooves 30 therein. It is of course to be understood that oil will also be distributed between the engaging surfaces of the valve sleeves and 10 the cap and head, and these surfaces may also if desired be provided with spiral grooves. I have shown the oil entering the valve cap at a point above the engaging surfaces of the sleeves as it is these particular 15 engaging surfaces which move at the highest relative speed. To prevent leakage of gas between the engaging surfaces of the cap 5 and the inner valve sleeve, the piston rings 19 are tensioned to bear outwardly 20 against the inner valve sleeve.

The inlet and exhaust ports 31 and 32 in the valve cap 8 register with the ports 12 and 13 in the head, respectively, and are brought into communication therewith 25 through perforations 33, 34, 35 and 36 in the valve sleeves arranged to be alternately brought into register with the intake and exhaust ports of the cap and head when the valve sleeves are oscillated. By thus 30 making the combustion chamber in the form of a truncated wedge with oblong ports arranged vertically in the parallel sides of the cone-shaped chamber near the apex, I obtain a quick charging and thorough 35 scavenging of the combustion chamber.

For oscillating the valve sleeves, the arms 20 and 21 are provided at their ends with perforated heads 37 and 38 which are connected through crank and pitman connections 39-40 and 41-42 with a valve driving shaft 43 geared to the engine shaft in the usual two to one ratio in any suitable manner not shown. In a multi-cylinder engine the valve shaft 43 may be common to the several sets of valves and the usual manifold connection provided for the intake and exhaust ports of the several valve caps.

For an engine of the four-cycle type as herein shown, the cranks 39 and 41 are set approximately at 90° and the openings in the valve sleeves arranged as indicated in dotted lines in Fig. 1. These parts are so arranged and adjusted in relation to each other and to the movement of the engine piston that the openings in the valve sleeves

are brought into and out of register with each other and with the intake and exhaust ports in the valve head and cap to alternately open and close said ports at the proper points in the cycle of the engine. 70 By setting each valve so that one of its openings will register with one of the ports of the combustion chamber when its operating crank is in one of its dead center positions, the valves are caused to attain their 75 slowest movement when the ports are wide open thus securing a long tarry at intake and exhaust and a quick opening and closing. It will be obvious that the timing of the valves in relation to the cycle of the engine may be varied as desired by the designer and according to the cycle of the engine by varying the set of the cranks or timing shaft and the relative positions of the valve openings. 80

While I have herein shown and described the combustion chamber as being separable from the engine cylinder, it is to be understood that, in making a complete engine embodying my invention, it is preferable to 90 make the combustion chamber integral with the engine cylinder, the valve cap only being detachable for purposes of assembling and repair.

It is also to be understood that I do not 95 limit myself to the particular embodiment of the invention herein shown and described, but contemplate all such modifications and variants thereof as may fairly fall within the scope of the appended claims.

Having thus described my invention what I claim and desire to secure by Letters Patent is—

1. The combination with an internal combustion engine having a cylinder and reciprocating piston, of a water jacketed head on the cylinder having a wedge-shaped combustion chamber formed therein and situated beyond the limit of the compression stroke of the piston, with intake and exhaust ports in the parallel sides of the chamber near the apex, said head having a cylindrical outer surface, piston rings carried by said head countersunk in the outside surface above and below said intake and exhaust ports, a valve sleeve seated around said head against said piston rings, a second valve sleeve seated around said first mentioned sleeve, a retaining cap fitted over said head and sleeves, said sleeves and cap having openings in opposite sides arranged to register with the intake and exhaust openings in the head, and operating arms carried by each of said sleeves projecting radially from the top thereof through the side of the cap for oscillating said sleeves to cause the openings to register with the openings or ports in the cap and head on opposite sides alternately. 110

2. The combination with an internal com- 130

- bustion engine having a cylinder and reciprocating piston therein, of a detachable head for the cylinder having a cylindrical outer wall, a combustion chamber formed 5 therein and a water jacket between the outer wall and the combustion chamber with intake and exhaust ports in the cylindrical wall communicating with the interior of the combustion chamber, a pair of telescoped 10 valve sleeves fitted around said head, a valve cap surrounding said head and sleeves having intake and exhaust ports registering with the intake and exhaust ports of the head, said sleeves having perforations arranged to be brought into and out of registration with said ports during oscillation 15 of said sleeves, operating arms for said sleeves extending outwardly and radially therefrom through said cap, the arm of the 20 inner sleeve extending outwardly and radially from the top edge thereof through a recess in the top of the outer sleeve and the arm of the outer sleeve extending outwardly and radially from the bottom of 25 said recess, and motion transmitting means between the engine piston and the said arms for oscillating the valve sleeves to open and close the intake and exhaust ports in timed relation with the movements of the piston.
- 30 3. The combination with an internal combustion engine having a cylinder and reciprocating piston therein, of a detachable head for the cylinder having a cylindrical outer wall, a combustion chamber formed 35 therein and a water jacket between the outer wall and the combustion chamber with intake and exhaust ports in the cylindrical wall communicating with the interior of the combustion chamber, piston rings nested in 40 the outer wall of said head tensioned to bear outwardly, a radial flange extending outwardly from the bottom of the outer wall of said head, an inner valve sleeve seated against said outer wall and said flange, an 45 outer valve sleeve seated against the outer surface of said inner valve sleeve and upon
- said flange, a valve cap covering said head and valve sleeves and seated upon the upper edges of said sleeves, the outer surface of the outer sleeve and the said flange, upper 50 and lower washers of bearing metal interposed between the upper and lower edges of the said sleeves and said cap and flange, and means for oscillating said sleeves.
4. The combination with an internal combustion engine, of a detachable head having a combustion chamber in the form of a truncated wedge with a cylindrical outer wall, a water jacket between the combustion chamber and said outer wall and intake and exhaust ports or ducts communicating with the combustion chamber through the parallel sides thereof near the apex, the said ports or ducts being oblong in cross section and arranged with the major axis 60 of the oblong parallel to the axis or median line of the wedge shaped combustion chamber, a radial flange on the bottom of the head for attachment to the engine cylinder, a pair of telescoped valve sleeves fitted 65 around the outer wall of said head and held against downward movement by said flange, a washer of bearing metal interposed between said sleeves and said flange, a valve cap surrounding said sleeves and having 70 an upper inwardly extending radial flange and a lower outwardly extending radial flange, said upper flange covering the upper edges of the sleeves and a portion of said head and said lower flange engaging with 75 the flange of the head, a washer of bearing metal between said upper flange and said sleeves, said cap having intake and exhaust ports registering with the corresponding 80 ports in the head, said valve sleeves having 85 perforations adapted to be brought into and out of registration with said ports during oscillation of said sleeves, and means for oscillating said sleeves.

In testimony whereof I affix my signature. 90

ALFRED ROSS JARMAN.
